UNITED STATES PATENT OFFICE.

PHILIP SCHEINER, OF BROOKLYN, NEW YORK.

DESIGN FOR A STAND FOR A DRINKING SET OR SIMILAR ARTICLE.

Application filed January 17, 1927. Serial No. 20,414. Term of patent 3½ years.

To all whom it may concern:

Be it known that I, PHILIP SCHEINER, a citizen of the United States, residing at Brooklyn, in the county of Kings and State of New York, have invented a new, original, and ornamental Design for Stand for a Drinking Set or Similar Article, of which the following is a specification, reference being had to the accompanying drawing, forming a part hereof.

The figure is a side elevation of a stand for a drinking set or similar article, showing my new design.

I claim:

The ornamental design for a stand for a drinking set or similar article, as shown.

January 7, 1927.

PHILIP SCHEINER.
